United States Patent Office.

WILLIAM G. CREAMER, OF BROOKLYN, NEW YORK.

Design No. 2,910, dated February 4, 1868.

DESIGN FOR A CAR-BASKET.

The Schedule referred to in these Letters Patent and making part of the same.

TO ALL WHOM IT MAY CONCERN:

Be it known that I, WILLIAM G. CREAMER, of the city of Brooklyn, county of Kings, State of New York, have originated and designed a new Pattern for Car-Baskets for railroad-cars, of which the following is a full, clear, and exact description, reference being had to the accompanying drawings making a part of this specification.

Car-baskets have usually been made by having one pattern to cast from, both ends being exactly alike, and they are also of inferior design. I make my car-baskets of brass, making a pattern for each of the designs shown in the accompanying drawing.

The drawings represent the ends only, and I desire only to secure a patent for the design, to prevent other parties from using my castings as patterns.

What I claim as my invention, and desire to secure by Letters Patent, is—
The design for a car-basket bracket or end, substantially as shown.
